OSCILLATOR CIRCUITS

De Witt R. Goddard, Riverhead, N. Y., assignor to
 Radio Corporation of America, a corporation of
 Delaware

Application March 14, 1932, Serial No. 598,567

4 Claims. (Cl. 250—36)

Heretofore in oscillators whose frequency of operation has been controlled by a resonant system such as a piezo-electric crystal, it has been customary to use separate crystal units consisting say of a crystal, tube and heater for changeover from one frequency of operation to another. Therefore, change of wave length required switching from one of the units formed of the crystal, heater and the like, to another.

10 It is the object of my present invention to provide a system wherein changeover may be accomplished more simply and cheaply and, in general, by change in voltage applied to a single tube with which there are associated a plurality of resonant systems preferably in the form of piezo-electric crystals.

My present invention is described more fully with the aid of the accompanying drawing wherein,

20 Figure 1 is a wiring diagram of my present invention illustrating the manner in which frequency changeover from one piezo-electric crystal to another may be accomplished by varying either the plate voltage or screen grid voltage or both 25 of an electron discharge device, and,

25 Figure 2 illustrates a complete transmitter wherein changeover from one crystal frequency to another may be accomplished by variation in plate voltage of the electron discharge device 30 forming the master control oscillator.

35 Referring to Figure 1 I have illustrated a tetrode or screen grid vacuum tube 2 having an electron emitting cathode 4, a control grid 6, a screen grid 8, and an anode or plate 10. The voltage to the screen grid is supplied through potentiometer 12 and variable tap 14, and, the voltage to the plate is also supplied from the potentiometer 12 to variable tap 16. Taps 14 and 40 16, of course, permit adjustment of the voltages applied to the plate and screen grid individually.

45 Between the control grid 6 and the cathode there is inserted a biasing resistor 18. Between the control grid 6 and screen grid 8 there is connected as illustrated a piezo-electric crystal B. In series with crystal B there is another piezo-electric crystal A connected between the control grid 6 and anode 10.

With the circuit as so far described, I have discovered that it is possible to have either crystal 50 oscillate by changing the relative voltages on the plate and screen grid. With the potentiometer delivering a maximum voltage to the anode or plate, crystal A will be found to be the frequency determining element as a result of which 55 output energy of a frequency determined by

crystal A may be derived from, for example, the resistor 20 in the plate supply lead.

This system then operates with the crystal A establishing feed back between the plate 10 and grid 6.

Now, to cause oscillation of the system under the control of crystal B, the plate voltage may be reduced by movement of tap 16 and if desired at the same time the screen grid potential may be increased. The circuit will then be found to 10 operate at the frequency corresponding to the frequency of the crystal B which is connected between the screen grid 8 and control grid 6. Under this condition, the control or screen grid 15 8 acts as a plate, regenerative action taking place through crystal B to the control grid 6. A resistance 22 may be inserted in the screen grid lead if desired.

To simplify operation, a switch 24 shown in the system shown in Figure 2, may be used. Connection to point b will reduce the relative voltage between the plate and screen grid and hence 20 crystal B will control the frequency of oscillations supplied through conductor 26 to the coupling tube or buffer amplifier 28. On the other hand, connection to point a will cause, by virtue 25 of increased potential to the plate, frequency controlling action by crystal A of oscillations generated by electron discharge device 2. If desired, in the system shown in Figure 2, change 30 from one frequency controlling system or crystal to another may be accomplished by leaving the switch on either point a or b and varying the potential applied to the screen grid 8 by varying the voltage applied to the screen grid by movement of screen grid voltage tap 14.

35 With the system shown in Figure 2, the output of the crystal controlled oscillator is fed to the coupling tube or buffer amplifier 28 which in turn excites a power amplifier 30 coupled to a radiating antenna 32. If desired, of course, frequency multipliers may be inserted between the buffer amplifier 28 and power amplifier 30 whose output may be varied by variation in voltage applied to the screen grid 34 thereof as indicated.

40 With the arrangement shown in Figure 2 also, code signaling at crystal controlled frequencies may be accomplished by switching from a point a to point b utilizing one crystal for indicating spaces, and the other for dots. In this event, of 45 course, the two crystals should operate at frequencies relatively close together. Also some form of relay rather than single pole double throw switch may be used for signaling in this way.

45 Also, the system shown in Figure 2 may be 55

utilized for secret signaling changeover in frequency being accomplished by some form of timing mechanism causing the switching from one crystal to another at certain time intervals, 5 for example, a switch-over from crystal A to crystal B once per second. Two receivers, one tuned to each wave will then give the total signal after combination of their final outputs.

Having thus described my invention, what I 10 claim is:

1. In apparatus for generating oscillations at either of a plurality of predetermined frequencies, an electron discharge device having an electron emitting cathode, a control electrode and a plurality of cold electrodes, a plurality of electromechanically resonant systems, circuits connecting separate resonant systems between the control electrode and each of said cold electrodes of said electron discharge device, and, means for 15 varying the voltage applied to one of the cold electrodes of said device whereby oscillations are generated in accordance with the voltage applied at a frequency determined by only one of said electromechanically resonant systems.
2. In apparatus of the character described, an electron discharge device having an electron emitting cathode, a control grid, and a plurality of cold electrodes, a pair of electromechanical vibrators serially connected between said cold electrodes, a connection from said control grid to a 20 point intermediate said serially connected vi-

brators, and, means for varying the voltage on one of said cold electrodes whereby said electron discharge device generates oscillations at a frequency determined by only one of said vibrators.

3. In apparatus of the character described, an 5 electron discharge device having within an evacuated container an electron emitting cathode, a control grid, a screen grid, and an anode, a pair of piezo-electric crystals serially connected, connected between said anode and screen grid, a 10 connection from a point intermediate said crystals to the control grid of said electron discharge device, and, means for varying the voltage of the anode with respect to the screen grid whereby either one or the other of said piezo-electric crystals determines the frequency of the output of 15 said electron discharge device.

4. In apparatus of the character described, an electron discharge device having an anode a 20 cathode a control grid and a screen grid, a pair of piezo-electric crystals serially connected, connected between said anode and screen grid, a resistance connected between said control grid and cathode, a connection from said control grid intermediate said piezo-electric crystals, and, means 25 for varying the voltage on said anode whereby either one of said piezo-electric crystals, dependent upon the voltage applied to said anode, controls the frequency of oscillations generated by said electron discharge devices.
